Primary Examiner — Kelley A Donnelly(74) *Attorney, Agent, or Firm* — John K. Park; Park Law Firm(57) **CLAIM**

The ornamental design for a travel tray, as shown and described.

DESCRIPTION

FIG. 1 is a perspective view of travel tray showing my new design;

FIG. 2 is a front plan view thereof;

FIG. 3 is a rear plan view thereof;

FIG. 4 is a left-side plan view thereof;

FIG. 5 is a right-side plan view thereof;

FIG. 6 is a top plan view thereof; and,

FIG. 7 is a bottom plan view thereof.

The broken line showing environment is for illustrative purposes only and forms no part of the claimed design.
